UNITED STATES PATENT OFFICE

2,676,346

SHOE FORMER

Jesse B. Gordon, San Angelo, Tex.

Application July 29, 1952, Serial No. 301,543

2 Claims. (Cl. 12—51)

1

This invention relates to new and useful improvements and structural refinements in devices for stretching and otherwise forming shoes, and the principal object of the invention is to provide a device of the character herein described, which may be conveniently and effectively employed for rolling raw edges of leather on the instep, raising the throat of the shoe so as to afford greater freedom at the upper edge thereof, turning out heel counter, stretching the toe boxing to relieve pressure on corns or bunions, and for many other similar operations.

Some of the advantages of the invention reside in its simplicity of construction, in its efficient and expeditious operation, and in its adaptability to economical manufacture.

With the above more important objects and features in view and such other objects and features as may become apparent as this specification proceeds, the invention consists essentially of the arrangement and construction of parts as illustrated in the accompanying drawing, in which:

Figure 1 is a perspective view of the invention in use;

Figure 2 is a side elevational view of the invention per se;

Figure 3 is a longitudinal sectional view of the invention; and,

Figure 4 is a side elevational view of the invention in its folded or inoperative position.

Like characters of reference are employed to designate like parts in the specification and throughout the several views.

Referring now to the accompanying drawings in detail, the invention consists of a shoe former which is designated generally by the reference character 10 and embodies in its construction a horizontally elongated base 12 which is of a substantially U-shaped cross-section, so as to afford a recess or grove 14. The bottom portion of the base is provided with a plurality of apertures 16 to receive fastening elements 18, whereby the entire device may be secured to a table top or shoe shelf 20.

One end portion of the base 12 is upturned and provided at its upper edge with a notch constituting a seat 22, the purpose of which will be herein-after described.

A pair of transversely spaced, upstanding ears 24 are provided on the base or support 12 adjacent the seat 22, these ears accommodating a fulcrum pin 26 on which is pivotally mounted one end portion of an elongated member 28.

The free end portion of the member 28 is of a

2

spool-shaped, diametrically stepped configuration so as to afford a shoulder 30, a pair of axially spaced bearing portions 32, 34 and a connecting shank 36, the bearing portions having mounted thereon a rotatable, tubular sleeve or roller 38.

Finally, a convex cap 40 is rotatably mounted by means of a pivot screw 42 at the free end of the member 28, the screw 42 extending into the bearing portion 34 and the cap 40 being disposed at the outer end of the roller 38 and independently rotatable relative thereto.

It is to be noted that the bearing cap 40 and the roller 38 are substantially equal in diameter.

When the invention is not in use, the member 28 is swung to a position as shown in Figures 3 and 4, wherein the roller 38 and the cap 40 are accommodated within the channel or recess 14. However, when the use of the device is desired,

the member 28 is swung outwardly so that it is supported by the seat 22 as shown in Figures 1 and 2, in which position the roller 38 and the cap 40 project outwardly beyond the adjacent end of the supporting base 12.

The roller 38 and the cap 40 may then be selectively employed in the manner shown in Figure 1

for smoothing raw edges of leather on the instep or throat of a shoe, or for raising the throat so as to afford greater freedom, or for applying pressure to the toe boxing of the shoe to provide

room for corns or bunions, and for many other similar forming operations.

The roller 38 and the cap 40 may then be selectively employed in the manner shown in Figure 1

for smoothing raw edges of leather on the instep or throat of a shoe, or for raising the throat so as to afford greater freedom, or for applying pressure to the toe boxing of the shoe to provide

room for corns or bunions, and for many other similar forming operations.

It is believed that the advantages and use of the invention will be clearly understood from the foregoing disclosure and accordingly, further description thereof at this point is deemed unnecessary.

While in the foregoing there has been shown and described the preferred embodiment of this invention, it is to be understood that minor

changes in the details of construction and arrangement of parts may be resorted to without departing from the spirit and scope of the invention as claimed.

Having thus described the invention, what is

claimed as new is:

1. A shoe former of the type described, comprising an elongated stationary support provided at one end thereof with a seat, an elongated member pivoted at one end thereof to said support at a point adjacent said seat, said member being swingable from an inoperative position above the support to an operative position wherein it engages said seat and projects beyond the support, a rotatable roller provided on the free end portion of said member, and a convex cap

3

rotatably mounted at the free end of the member, said cap being substantially equal in diameter to said roller and rotatable independently thereof.

2. A shoe former comprising a stationary elongated support, an elongated member pivoted at one end to said support intermediate the ends of said support, said member being swingable from an inoperative position overlying said support to an operative position projecting axially beyond the support, an intermediate portion of 10 said member resting on said support when in operative position, a roller rotatably mounted on

the free end portion of said member and a cap rotatably mounted on the free end of said member and being rotatable independently of said roller.
